DISPENSING, SELF-LOCKING CLOSURES
Paul Lee, 1809 E. Clearfield St., Philadelphia 34, Pa.
Filed Nov. 6, 1961, Ser. No. 150,221
3 Claims. (Cl. 215—74)

The present invention relates to a closure and more particularly to a dispensing self-locking closure.

Objects of this invention are to provide such a closure which is of simple compact construction, readily and economically manufactured on a mass production basis, is sturdy and reliable in performing its functions, while being easy to operate and has sanitary provisions to prevent contamination of the sealed contents at all times.

More specific objects of the present invention are to provide a closure readily adaptable to integral construction, having completely self contained detents, having positive displacement detents lockable in the closed position, operable through a simple axial motion, permitting dispensing while attached to the container and attachable to the container which it seals.

Other objects of the invention will in part be obvious and will in part appear hereinafter.

The invention accordingly comprises the features of construction, combination of elements and arrangement of parts, which will be exemplified in the construction hereinafter set forth, and the scope of the invention will be indicated in the claims.

For a more complete understanding of the nature and objects of the invention, reference should be had to the following detailed description taken in connection with the accompanying drawings, in which:

FIG. 1 is a side elevation view of the closure in the closed position. Part of the container to which it has been applied is shown in dash outline.

FIG. 1a is a sectional view taken along the line 1a—1a of FIG. 1.

FIG. 2 is a side elevation view of the closure in the open position. Part of the container to which it has been applied is shown in dash outline.

FIG. 3 is a partial cross section view of the plug element of the closure showing in detail the surface contour of the plug where it is intended to contact the sides of the orifice. The section is taken at an axial plane through a diameter.

FIG. 4 shows an abbreviated form of the closure in a side elevation view.

FIG. 5 shows a plan view of the closure in FIG. 4 sighting from the top.

FIG. 6 is a side elevation view of the closure with certain elements rearranged.

FIG. 7 is a side elevation view of the closure showing a special form of positive displacement detent at the inner end.

FIGURE 1 illustrates the closure in the closed position and FIGURE 2 illustrates the open position. The numbers on the illustration refer to the various parts of the invention as described hereinafter.

The main body of the closure is generally cylindrical in appearance, the bottom half of which may be considered as the inner portion and the upper half the outer portion. The inner portion 1, of the closure is comprised of the inner detent elements, the head core 3, the flexible flange 2, the large groove 10, and the undercut groove 11, and the plug 4, with its flexible face 16, and its diametral rib 17.

The head core 3 is a rigid disklike structure tapered on the free end and of a size having minimum clearance between its sides and the orifice. The flexible flange 2, above the head core 3, is of sufficiently larger diameter than the said head core 3, as to enable it to overlap the top edge of the head core 3. The said flange 2, is flexible

2

while being sufficiently thick as to prevent the re-entry of the head core 3, into the orifice while it is overlapping the head core 3. The large groove 10 is of sufficient depth and width to receive the flexible flange 2, when the said flange 2 is in collapsed state. The undercut groove 11, enables the flexible flange 2 to collapse to a smaller diameter in order that the said flange 2 will clear the orifice walls.

The plug 4 is preferably of rigid form with the sides 10 having a flexible face 16 to ensure firm and continuous contact around the orifice. The flexible face 16 consists of very small flexible riblike structures on the contact face of the plug 4 as illustrated in FIGURE 3.

Connection between the plug 4 and the dispensing tube 12 which forms the largest part of the outer portion, is preferably through a diametral rib 17 above the plug 4 and local axial extensions 13 of the dispensing tube 12 which attach to the ends of the diametral rib 17.

Preferably the outer portion of the closure takes the 20 form of a dispensing tube 12, having wall thickness in at least one place sufficient to contain a recess 7 on the outer surface. Attached to the outer side of the tube 12 also is a tab 5 which may be collapsed or retracted completely into the recess 7. When extended, the tab 5 acts 25 as a detent to prevent axial movement of the closure into the orifice and when retracted or collapsed, the tab 5 does not hinder axial travel of the closure.

The flexible connection 15 to the cap 6 may be attached to the outer side of the dispensing tube 12 as shown in 30 FIGURES 1 and 2, or to the upper outer side of the tab 5 as shown in FIGURES 6 and 7. The said flexible connection 15 also functions as a stop to excessive axial travel inward of the closure.

The location of the various parts are determined to a 35 great extent by the length of the orifice. The tab 5 extends over the top edge of the orifice wall when the flexible flange 2 is in contact with the bottom edge of the orifice wall. The flexible connection 15 stops axial travel when the plug 4 has cleared the bottom end of the 40 orifice sufficiently to permit passage of material into the dispensing tube 12 in such quantity as desired.

The dispensing tube 12 is of a size to fit sufficiently 45 tight in the orifice as to maintain the closure in position while material is being dispensed and exclude said material from passing between the orifice wall and the dispensing tube 12.

The flexible connection 15 is preferably of sufficient 50 stiffness to hold the cap 6 clear of the dispensing tube 12 while the closure is stationary. When desirable, the cap 6 provides a sanitary cover for the dispensing tube 12 but is not a necessary part of the invention. Any convenient handle may be attached in place of the flexible connection 15 and the cap 6 for means of exterior control.

The form of the inner detent used in the closure illustrated in FIGURE 7 is preferable when it is desired that 55 removal of the closure from the container be possible after being rendered captive thereto. The flexible bar 21 extends diametrically outward overhanging the head core 31. The recess 19 and recess 20 are each capable 60 of containing the flexible bar 21 when it is bent or collapsed thereto. The recess 22 prevents total collapse or retraction of the flexible bar 21 when the said bar is directed thereto. Thus when the bar 21 is directed into the recess 22 detent action occurs, resulting from the 65 protrusion of the bar 21 past the circumference of the head core 31. Two or more of this form of detent are preferable in each closure.

The closure is preferably constructed integrally of a 70 naturally flexible material such as polyethylene, although any other material or combination of materials which will impart to the completed closure the physical characteristics which are described above may be used.

The flexible face of the plug may take any of numerous different configurations to satisfy the needs of different sealing requirements, such as duration of usage, tightness of sealing, ease of operation or other conditions. A more easily slideable closure can be produced by having the sealing function at the lower end of the dispensing tube 12 and at the lower side of the plug 4 fulfilled by a circumferential lip tapering diametrically outward to a knife-edge. Such a lip would provide a wiping seal against the sides of the orifice. Another configuration could have a plurality of such lips as described above in gradually increasing sizes so that one of the lips would provide an optimum fit in cases where variations occur in orifice dimensions.

The closure may be used in sealing any orifice and is not limited to use in the orifice of a container.

The closure is put in use by inserting it into the orifice of the container to be sealed. This is accomplished readily without using great force because the closure is designed to fit slideably within the orifice which it seals.

The closure is inserted into the orifice with the head core 3 first. The head core 3 is tapered and of the size which enables it to slide easily through the orifice. Second, continued axial motion of the closure causes the flexible flange 2 to contact the outer end of the orifice wall and be forced to collapse into the groove 10. The undercut groove 11 provides clearance. Third, the plug 4 is pushed into the orifice followed by the connection to the dispensing tube 12 diametral rib 17 and axial extensions 13 of the dispensing tube 12. Fourth the tab 5 is depressed into recess 7, while the dispensing tube 12 slides through the orifice until axial motion is stopped by the flexible connection 15, attached either to the side of the dispensing tube 12, as shown in FIGURE 2, or the tab 5, as shown in FIGURE 6. In this position, the inner portion of the closure including the plug 4 has cleared the inner end of the orifice and the flexible flange 2 has returned to its original position overlapping the head core 3. The closure is now drawn outward through the orifice until axial motion is stopped by the inner detent, the flexible flange 2, preventing the head core 3 from re-entering the orifice. In this position, shown in FIGURE 1, the plug 4 is in the orifice and the latter is sealed by the tight fit of the plug 4 therein. Also in this position the tab 5 of the outer detent extends over the outer end of the orifice walls. Thus the closure is locked in place in the closed position by the cooperation of the inner and outer detents.

To release the closure, the tab 5 is collapsed into the recess 7, and the closure is pushed inward through the orifice until stopped by the attached flexible connection 15. In this position as shown in FIGURE 2 flowable material may enter the opening 8 and pass through the dispensing tube passage 9. Thus material is dispensed while the closure is attached to the container.

Operation of the modified form of closure as shown in FIGURES 4 and 5 is largely similar to the above. This form of the closure may be used where a tight seal is not required. The inner and outer detents function as previously described. In this case the flexible flange 2 also blocks the inner end of the orifice thus sealing the container. Dispensing of material takes place readily through the orifice of the container which is not blocked when the closure is in the open position.

Operation of the closure shown in FIGURE 6 is identical with that shown in FIGURES 1 and 2. In addition, the flexible connection 15, as attached to the tab 5 acts as a bracing member to hold the tab 5 in the extended position. Thus the closure is locked more securely in the closed position.

The form of the closure illustrated in FIGURE 7 permits its repeated insertion and removal from the orifice which it seals. A clockwise turning motion is added while inserting the closure axially into the orifice. As the overlapping portion of the flexible bar 21 bears against

the outer end of the orifice wall, the helical motion imparted to the closure causes the said flexible bar 21 to bend or collapse completely into the recess 20. Thus the closure can easily enter the orifice. Axial motion with the tab 5 collapsed into the recess 7 is continued until stopped by the flexible connection 15, attached to the tab 5.

The container is sealed by drawing the closure outward through the orifice and simultaneously turning it clockwise causing the flexible bar 21 to bend, as it encounters the inner end of the orifice wall, into the small recess 22, which prevents the said flexible bar 21 from further bending. Thus the flexible bar 21 overhangs the head core 31 and prevents the head core 31 from re-entering the orifice. The outer detent action is as previously described.

The closure is removed from the orifice by drawing the closure outward and simultaneously turning it counter clockwise causing the flexible bar 21 to collapse completely into the recess 19, thus permitting unhindered withdrawal of the closure from the orifice.

I claim:

1. In a container closure for insertion in the orifice of a container, a flexible body having a generally longitudinally extending discharge opening a passage extending into the discharge opening between the two ends of the closure and adapted to be open to the contents of the container when the closure is inserted into the container and to be closed from the contents of the container when the closure is moved outwardly in the orifice, said body having plug means located inwardly of said passage and sealing on the orifice when the container closure is in closed position, means for imprisoning said closure in said container comprising a flexible annular flange of larger diameter than the orifice located on said body inwardly of the plug means and adapted to be located in a position beyond the diameter of the orifice, said body having a groove located outwardly of said flange and large enough to permit collapse of said flange into said groove when said closure is inserted into said orifice, said body having a second groove located inwardly of said flange, and an annular abutment located inwardly of said flange and beyond said inwardly located groove extending out to substantially the diameter of the orifice and adapted to engage said flange to imprison said closure when an effort is made to withdraw the same from the orifice.

2. A container closure of claim 1, having a lateral recess at the outside of said flexible body located between said passage and the outer end of said closure, and a detent tab hingedly mounted and resiliently urged to an outer position beyond the diameter of said orifice at which it limits inward movement of said closure to a position preventing flow of liquid through the orifice and compressible into said recess to permit movement of said closure to a position permitting flow of liquid through the orifice.

3. A container closure of claim 1, in combination with a limit stop means located extending from said body and located at the outer end thereof and adapted to insertion of the closure into the container to a position permitting flow of liquid through the orifice.
